UNITED STATES PATENT OFFICE.

PAUL HARTMANN, OF BROOKLYN, NEW YORK, ASSIGNOR, BY DIRECT AND MESNE ASSIGNMENTS, OF ONE-HALF TO CHARLES L. EIDLITZ, OF NEW YORK, N. Y., AND ONE-HALF TO METROPOLITAN ELECTRIC MFG. CO., A CORPORATION OF NEW JERSEY.

ELECTRICAL RECEPTACLE.

Application filed September 30, 1922. Serial No. 591,483.

To all whom it may concern:

Be it known that I, PAUL HARTMANN, a subject of the King of Denmark, residing at Brooklyn, in the county of Kings and 5 State of New York, have invented certain new and useful Improvements in Electrical Receptacles, of which the following is a full, clear, and exact description.

My invention relates to electrical receptacles, switch devices and the like, such as 10 are commonly set into the wall, and relates more particularly to the means for securing such receptacles or devices to the wall box or other supporting member in the wall. 15 The so-called flush or base-board receptacles, for example, have a moulded porcelain or other composition body member in which are contained the electrical contact parts, and it is common practice to secure this 20 body member to the wall box by means of a metallic strap which surrounds the body member on three sides and has out turned ends which are screwed to the wall box. Such straps are usually fastened to the body 25 member by means of one or more screws which pass through the strap and into the rear face of the body member, and it will be understood that this not only necessitates the provision of some metallic member in 30 the body in which screw threads can be formed, but also adds to the labor and expense of assembly.

An object of my invention is to provide a construction for this purpose which will be 35 simpler and cheaper and will facilitate the operation of assembly. Another object is security of attachment combined with reasonable facility in disassembly, whenever for any reason it becomes necessary to 40 move the strap from the body member. Still other objects and advantages of my invention will appear from the following description.

In accordance with my invention I so construct the strap and body that they will 45 automatically lock together as they are assembled. This is perhaps best accomplished by providing in one or both arms of the U-shape strap, a resilient, struck-out tongue 50 which projects slightly inwardly and catches over a shoulder in the body, formed by making a depression in the end wall, as the strap is moved to its place over the body.

I shall now describe the illustrated embodiment of my invention, and shall thereafter point out my invention in claims. 55

Fig. 1 is a side elevation, partly in section, of a receptacle embodying my invention in place in a wall;

Fig. 2 is a transverse section of the same 60 on line 2—2 of Figure 1;

Fig. 3 is a detail in perspective of my improved strap.

The receptacle body 1 is molded of porcelain or a suitable composition and may be 65 of any desired internal construction. A groove 2 is formed around three sides of the receptacle, namely, the bottom and its two ends, the depth and width of the groove being such as to take the ordinary metallic 70 strap. A relatively narrow notch or inwardly extending off-set is formed in the groove 2 in each end wall by providing a recess or slot 3 in the upper end of the groove in each end wall, which slots terminate in a shoulder 75 4 a substantial distance back from the front face of the receptacle body.

The retaining strap 5 is of generally U-shape with the ends turned outwardly and provided with screw holes in the usual way. 80 In each arm of this strap there is struck out a longitudinal spring tongue portion 6 attached at its upper end and bent inwardly so that its lower or free end extends slightly beyond the inner face of the arm. The strap 85 is of such a size to fit snugly within the groove 2 and it is assembled on the body by entering the groove between the two arms of the strap and pressing the strap and body together until the tongues 6 snap over the 90 shoulders 4, as shown in Figures 1 and 2. The two members are thus firmly secured together, but may be easily separated by inserting an implement between the end walls 95 of the body and the inner faces of the arms of the strap until the tongues 6 are forced out enough to release them from the shoulders 4.

The receptacle is shown in Figures 1 and 2 secured in a wall box 7 within a baseboard 100 8. The wall box is provided with adjustable ears 9 of usual construction, and the outwardly turned ends of the strap 3 extend over these ears with their screw holes registering with those in the ears, so that a single 105 screw on each end secures the two members

together and to the baseboard. The whole device is then covered with a suitable plate 10.

It is obvious that various modifications 5 may be made in the construction shown in the drawings and above particularly described within the principle and scope of my invention.

I claim:

1. For an electrical receptacle or the like, a body member recessed in at least one of its ends to provide a transverse shoulder at the rear end of the recess, and a substantially U-shape strap embracing the body member along the latter's rear face and two end walls and having in at least one of its arms an inwardly and rearwardly extending spring tongue adapted to be received in the said recess and snap over the said shoulder 15 of the body member as the parts are assembled, whereby the parts are positively locked against separation and may be unlocked by
- 20

a tool inserted behind the tongue from the front end of the recess.

2. For an electrical receptacle or the like, 25 a body member recessed to receive a strap across its rear face and along its end walls and having the recess in each end wall deepened from the outer face of the body member for a substantial distance rearwardly and 30 terminating in a shoulder, and a substantially U-shape strap seated in said recess and having in each arm a struck-out inwardly and rearwardly extending spring tongue in position to snap over the respective 35 shoulder as the parts are assembled, whereby the parts are positively locked against separation and may be unlocked by a tool inserted behind the tongues from the open end of the respective slots.

In witness whereof I hereunto subscribe my signature.

PAUL HARTMANN.
